UNITED STATES PATENT OFFICE.

STANLEY SKURNIAK, OF CHICAGO, ILLINOIS.

WINDOW GUARD.

Application filed June 30, 1922. Serial No. 571,889.

To all whom it may concern:

Be it known that I, STANLEY SKURNIAK, a citizen of Poland, residing at Chicago, in the county of Cook and State of Illinois, have invented new and useful Improvements 5 in Window Guards, of which the following is a specification.

This invention relates to protective devices for banks, stores, booths, etc., whereby 10 the persons behind a counter or window, or in a booth, are protected against attacks by robbers.

The object of the present invention is to provide a very efficient and reliable device 15 of the kind stated and to this end it consists in a novel combination and arrangement of parts to be hereinafter described in detail and claimed.

In order that the invention may be better 20 understood, reference is had to the accompanying drawings, wherein:

Figure 1 is an elevation of the structure to which the invention is applied; Fig. 2 is an enlarged vertical section on the line 25 2-2 of Fig. 1; Fig. 3 is a horizontal section on the line 3-3 of Fig. 1; Fig. 4 is an enlarged horizontal section on the line 4-4 of Fig. 2; Fig. 5 is a cross-section on the line 5-5 of Fig. 4; Fig. 6 is a sectional detail 30 on the line 6-6 of Fig. 3; Fig. 7 is an elevation of a fragment of the protective curtain; Fig. 8 is a vertical section on the line 8-8 of Fig. 7; Fig. 9 is a cross-section on the line 9-9 of Fig. 8; Fig. 10 is an elevation, 35 partly in section, showing another embodiment of the invention; Fig. 11 is a horizontal section on the line 11-11 of Fig. 10; Figs. 12 and 13 are vertical sections on the lines 12-12 and 13-13 of Fig. 10; Fig. 40 14 is an elevation of a detail; Fig. 15 is a vertical section on the line 15-15 of Fig. 14.

Figs. 1 to 9 show the invention applied to the window of a bank or other office. The 45 jambs of the window are shown at 20, and near the bottom thereof is a door 21 for entrance to and exit from the room, compartment or the like. The protective device is a curtain 22 made up of perforated metal 50 strips which are hingedly connected to obtain sufficient flexibility to permit the curtain to be wound on a roller 23 and to be unwound therefrom. This roller is located at the bottom of the window, inside the 55 room, compartment or the like, and below the floor 24 thereof. The curtain 22 is suit-

ably fastened at one end to the roller 23, and to the other end of the curtain are made fast hauling lines 25 which extend upwardly to guide pulleys 26 at the top of the window, and after passing over the latter, said lines extend downwardly and have weights 27 connected to their lower free ends. When the curtain is not in use, it is rolled up on the roller 23, and so held by a means to be 60 presently described. The winding of the curtain on the roller elevates the weights 27, and when the curtain is released the weights descend and draw the curtain off the roller to close up the window, the curtain traveling upwardly as the weights descend. The weights and the hauling lines 70 seat in housings in the jambs 20, and in the bottom of these housings are located spring bumpers 28 which are engaged by the 75 weights at the limit of their downward travel. Adjacent to the roller 23, and parallel thereto is a cutting guide roller 29.

The curtain 22 is held wound on the roller 23 by a brake band 30 engageable with a 80 brake drum 30^a on one end of the shaft 23^a of the roller. One end of the brake band is anchored to a support 31 and its other end is fastened to a coiled spring 32 which operates to tighten the band around the 85 drum. The spring is anchored to a suitable support 33. The last-mentioned end of the brake band is also connected to the outer end of a rocker arm 34 extending laterally from a rock shaft 34^a to which is connected one 90 end of a lever 35 having connected to its other end the stem 36 of a foot pedal 37, said stem passing upwardly through a hole in the floor 24 to locate the pedal close to and above the latter. The rock shaft 34^a also 95 has a rocker arm 38 extending in the opposite direction from the arm 34, to which arm 38 is connected a coiled spring 39 anchored to the floor 24, beneath the latter. It will be evident from the foregoing that 100 when the pedal 37 is depressed, the lever 35 swings in a direction to cause the arm 34 to expand the spring 32 and thus allow the brake band to slacken and release the drum 30^a, whereupon the curtain 22 is released and 105 unwound from the roller 23, and drawn upwardly to operative position by the weights 27. Upon releasing the foot pedal 37, the spring 39 restores the same to its normal position, and the brake band again grips the 110 drum.

The winding gear whereby the curtain

22 is rewound on the roller 23 comprises the following parts:

One end of the roller shaft 23^a is fitted with a bevel gear 40 which is in mesh with 5 a bevel gear 41 on a shaft 42 having one of its ends journaled in an axial recess in the adjacent end of an axially aligned shaft 43. The shafts 42 and 43 are connected to turn together, and the shaft 42 is slidable 10 in the direction of its length to take its gear 41 out of mesh with the gear 40, this operation being effected by a shifter 44 connected by a link 45 to a crank arm 46 on a tubular vertical shaft 47 fitted at its 15 upper end with an operating handle 48 provided with a catch 49 to lock the same. Through the shaft 47 extends a shaft 50 having its lower end fitted with a bevel gear 51 which is in mesh with a bevel gear 52^a on 20 the shaft 43. The upper end of the shaft 50 is fitted with a bevel gear 51^a which is in mesh with a bevel gear 52^a on the shaft of a crank handle 53. The gears 51^a and 52^a are enclosed in a housing 54 25 mounted on the wall of the office or other compartment to which the invention is applied.

Upon swinging the handle 48 in the proper direction, the shaft 42 is slid to 30 disengage its gear 41 from the gear 40. This will be the normal position of these parts. If now it becomes necessary to use the curtain, the foot pedal 37 is depressed, whereupon the brake mechanism herein- 35 before described releases the roller 23 and the curtain 22 is at once drawn upwardly to protective position by the weights 27. To rewind the curtain on the roller, it is necessary only to shift the shaft 42 in a direction 40 to bring its gear 41 in mesh with the gear 40, and then to operate the crank handle 53, whereupon through the gearing herein- before described the roller 23 is rotated to 45 wind the curtain thereon.

45 Figs. 7 to 9 illustrate the connection between the curtain 22 and the hauling lines 25. One end only of the curtain has been shown, it being understood that the fixtures at the two ends are alike. To the 50 free end or the top of the curtain are riveted two outwardly facing angle bars 55, the flanges of these bars being cut away near the ends to permit a pair of bracket members 56 to be riveted thereto. The upper 55 ends of these bracket members carry a cross pin 57. The end of the line 25 is formed into an eye 58 through which the cross pin 57 passes. Below the cross pin 57, the bracket members 56 carry anti-friction rollers 59 which run on the opposite side walls 60 of a guide channel mounted on the jamb 20.

65 Figs. 10 to 15 disclose a counter or show case guard consisting of a curtain 60 which travels downwardly to protective position.

This curtain is fastened to a winding roller 61 suitably supported at the top of the structure. In front of the roller 61 is a guide roller 62 over which the curtain passes. To the bottom of the curtain, at 70 each end thereof, is fastened a weight 63, the connection being made by bracket plates 64 equipped with anti-friction rollers 64^a which travel in guide channels 65. The weights 63 are located beyond the side edges 75 of the curtain to travel in a housing 63^a containing a spring bumper 65^a which is engaged by the weights at the limit of the downward travel of the curtain.

The curtain 60 is held wound up on the roller 61 by a brake band 66 passing around a brake drum 67 on one end of the roller shaft 68. As in the structure first described, the brake band is held taut by a spring 69, and released by a rod 70 extending downwardly therefrom, its lower end being operatively connected to a foot rail 71 so that when the latter is pushed forwardly, the brake is operated to release the roller 61 and allow the curtain 60 to be unwound 90 and pulled downwardly by the weights 63.

The roller shaft 68 is equipped at one end with a bevel gear 72 which is in mesh with a bevel gear 73 on a vertical shaft 74 connected at its lower end by a bevel gearing 75 to a crank-handle 76. This gearing operates in the same manner as the winding gear hereinbefore described for winding the curtain 60 back on the roller 61. The shaft 74 is movable by a handle 77 in the direction of its length to disengage the gears for the same purpose as the shaft 42 hereinbefore described.

I claim:

1. A guard of the character specified comprising a roller, a curtain connected to the roller, means for drawing the curtain upwardly to operative position, a pinion having connection with said roller, a second pinion engaged with said first named pinion, 105 a driven shaft connected to said second named pinion and including a pair of slidably connected aligned sections, a driving shaft having connection with one of the sections of said driven shaft, a tubular member receiving said driving shaft and having its lower end provided with a radial member, a link connected to said radial member, means connecting the link to one of the sections of said driven shaft whereby the rotation of said tubular member results in the longitudinal movement of said driven member and the said second named pinion, and a handle connected to said tubular member at the upper end thereof and adapted to be 110 manually engaged for turning the tubular member and thereby releasing the second named pinion from engagement with the first named pinion.

2. A guard of the character specified com- 130

prising a roller, a curtain connected to the roller, means for drawing the roller upwardly to operative position, a pinion having connection with said roller, a second pinion 5 adapted for engagement with said first named pinion, a driven shaft connected to said second named pinion, a driving shaft having connection with said driven shaft, a tubular member rotatably receiving said 10 driving shaft, means operated by said tubular member for releasing said second named pinion from engagement with said first named pinion, a hand operated crank connected to said tubular member, and means 15 whereby said driving shaft may be manually turned.

3. The construction set forth in claim 2, and a foot controlled brake normally holding said curtain in inoperative position.

4. A guard of the character specified comprising a roller, a curtain connected to the roller, a brake band associated with the roller, a rocker arm connected to the brake band, spring means connected to the rocker arm for urging the brake band to operative 20 position, foot controlled means for releasing said brake band, weight actuated cables for moving said curtain to operative position, and means adapted for connection with said roller to wind the curtain thereon. 25

In testimony whereof I affix my signature. 30
STANLEY SKURNIAK.
